UNITED STATES PATENT OFFICE

110,534

DESIGN FOR A BROOCH OR THE LIKE

Oreste J. Agnini, Maywood, and Mary C. Granville, Chicago, Ill., assignors to Agnini & Singer, Chicago, Ill., a co-partnership composed of Oreste J. Agnini and Ralph W. Singer

Application May 14, 1938, Serial No. 77,184

Term of patent 3½ years

To all whom it may concern:

Be it known that we, Oreste J. Agnini and Mary C. Granville, both citizens of the United States, residing, respectively, in Maywood and Chicago, county of Cook, and State of Illinois, have invented a new, original, and ornamental Design for a Brooch or the like, of which the following is a specification, reference being had to the accompanying drawing, forming a part thereof, and in which

Fig. 1 is a front view; and
Fig. 2 a side view of a brooch showing our new design.

We claim:

The ornamental design for a brooch or the like, as shown.

ORESTE J. AGNINI.
MARY C. GRANVILLE.
